UNITED STATES PATENT OFFICE.

JERVIS R. HARBECK, OF CHICAGO, ILLINOIS, ASSIGNOR TO AMERICAN CAN COMPANY,
OF NEW YORK, N. Y., A CORPORATION OF NEW JERSEY.

SODA-STRAW HOLDER.

1,198,027.

Specification of Letters Patent. Patented Sept. 12, 1916.

Application filed December 4, 1913. Serial No. 804,574.

To all whom it may concern:

Be it known that I, JERVIS R. HARBECK, a citizen of the United States, residing in Chicago, in the county of Cook and State of Illinois, have invented a new and useful Improvement in Soda-Straw Holders, of which the following is a specification.

This invention relates to improvements in soda straw holders.

10 An object of the invention is to provide a sanitary, sheet metal soda straw holder from which the straws may be readily and conveniently removed one by one as desired and so arranged that the user removes the straws 15 by inserting his fingers or finger and thumb through a recess in the side wall of the holder to grasp the straws.

Another object of the invention is to provide a soda straw holder of the type above 20 indicated in which automatically operating means are provided for keeping the straws adjacent the opening from which they are removed.

The invention furthermore consists in the 25 improvements in the parts and devices and in the novel combinations of the parts and devices herein shown, described or claimed.

In the drawing forming a part of this 30 specification, Figure 1 is a front elevation of a soda straw holder embodying my improvements. Fig. 2 is a vertical, sectional view taken substantially on the line 2—2 of Fig. 1. Fig. 3 is a horizontal, sectional view taken substantially on the line 3—3 of 35 Fig. 2 and Fig. 4 is a top plan view of the holder with the cover in open position, the latter being shown in section.

In said drawing the body 10 of the holder is shown as comprised of a single piece of 40 sheet metal, the edges of which are united by a lock seam 11 on the rear side, said body having a straight rear wall 12, side walls 13 at substantially right angles thereto and angularly disposed front faces 14, the cross 45 sectional shape of the body being more or less "plow shaped". The sheet metal body is mounted on a sheet metal base 15 by tongue and slot connections, as shown in Fig. 2. The height of the body is such that the straws may be placed and held therein 50 in a vertical position, as indicated in Figs. 1 and 2 and on the front thereof and at the angle formed between the two front faces 14—14, the body is provided with a cut-out

portion or recess 16 which is narrow at the 55 top thereof, as indicated at 17 and just wide enough to permit a single straw to pass therethrough, said recess being gradually widened downwardly, as indicated at 18 and at the bottom is provided with an enlarged 60 more or less circular portion 19 through which the user may place his fingers or finger and thumb to extract straws. On a cross rod 20 secured to the body member at the rear thereof is pivotally mounted a presser 65 plate 21 under the control of a coiled spring mounted on the rod 20. The lower edge 23 of the plate 21 is curved (see Fig. 3) and, as will be understood, the plate presses the straws forwardly into the angle formed between the front faces 14—14. A cover or lid 24 having a depending telescoping flange 25 is pivoted to the body at 26, the flange 25 being provided with a cut-out portion 27 in alignment with the upper narrow portion 75 17 of the recess 16 to thereby prevent interference during the removal of the straws. The top of the body 10 at the front portion thereof is provided with a plate 28 having a small recess 29 therein just large 80 enough to permit one straw at a time to pass therethrough, see Fig. 4. As will be understood, the function of the plate is to prevent more than one straw at a time from being removed and also to prevent the 85 straws, as they are lifted out, from lifting up the pivoted cover 24.

From the preceding description it will be seen that the holder which I have provided is relatively inexpensive to manufacture, 90 provides for the sanitary retaining of the straws, prevents the removal of more than one straw at a time, and permits of the easy removal of the straws as desired by the user.

Although I have herein shown and de- 95 scribed what I now consider the preferred embodiment of my improvement, yet it will be understood that various changes and modifications may be made without departing from the spirit of the invention, and all 100 such changes and modifications are contemplated as come within the scope of the claims appended hereto.

As will be noted, the spring pressed plate 21 engages the straws below the level of the 105 bottom of the recess 16 so that it will have no tendency to press the straws out through the recess, but on the other hand will serve

to keep the straws in a vertical position and furthermore, the converging front walls 14 on the body member form a guide directing the straws toward the opening from which 5 they are removed.

I claim:—

1. A straw holder comprising a body adapted to hold straws therein, said body having a lateral straw delivery opening, 10 through which straws may be successively grasped and withdrawn by the fingers; and means for pressing the straws toward said opening; the said body having means for preventing the straws from escaping from 15 said opening until they are intentionally withdrawn.

2. A soda straw holder having a body member, the front of which is formed with the two walls thereof angularly arranged 20 relative to each other, said body having a slot therein at the vertical angle between said walls, said slot being narrow at its upper end and wider at its lower end, and means for pressing the straws toward the 25 said opening, substantially as specified.

3. A soda straw holder of the character described including, in combination: a sheet metal body having an opening therein in 30 its front wall, said opening being large enough at the bottom to permit the user's fingers to pass therethrough to grasp a straw and narrow at the top; and means for pressing the straws toward the front of the body adjacent said opening, substantially as 35 specified.

4. A soda straw holder of the character described including, in combination: a sheet metal body member having the front side thereof formed with converging surfaces 40 and provided with a slot at the angle formed between said surfaces, and through which the straws are adapted to be withdrawn; and spring controlled means within the body member normally pressing the straws to-

ward the front thereof, substantially as 45 specified.

5. A soda straw holder of the character described comprising, in combination: a sheet metal, vertically extending body member provided with an opening in the front 50 thereof, said opening extending entirely to the top of the body and being narrow at the top and wide enough at the bottom to permit the user's fingers to enter therein to grasp a straw; a cover for said body member and 55 means for pressing the straws toward the said opening, substantially as specified.

6. A soda straw holder of the character described comprising, in combination: a sheet metal body member having converging 60 front walls and provided with a slot where said walls meet, said slot being narrowed at its upper end to prevent more than one straw at a time from being drawn therethrough and widened at its lower end to permit the 65 user's fingers to be inserted therethrough to grasp a straw; a plate secured to the top of said body adjacent the top of the wall therein, said plate having a recess permitting the passage of a single straw there- 70 through; and a cover for said box.

7. A soda straw holder of the character described comprising, in combination: a sheet metal body member substantially plow- 75 shape in cross section and having a recess in the front thereof, said recess being narrow at the top and wide at the bottom; a plate secured to the top of the body member adjacent said slot; a cover for said body member; and a spring controlled plate normally 80 pressing the straws toward the front of the box, substantially as specified.

Signed this 1st day of December, 1913, in the presence of two subscribing witnesses.

JERVIS R. HARBECK.
